DESIGN FOR A LADY'S SHOE OR SIMILAR ARTICLE

David E. Levin, Brooklyn, N. Y., assignor to I. Miller & Sons, Inc., Long Island City, N. Y., a corporation of New York

Application November 6, 1947, Serial No. 142,355

Term of patent 3½ years

(Cl. D7—7)

To all whom it may concern:

Be it known that I, David E. Levin, a citizen of the United States of America, residing at Brooklyn, New York, county of Kings, and State of New York, have invented a new, original, and ornamental Design for a Lady's Shoe or Similar Article, of which the following is a specification, reference being had to the accompanying drawings, forming a part thereof.

In the drawings:

Fig. 1 is a perspective view of a lady's shoe showing my new design;

Fig. 2 is a top plan view thereof;

Fig. 3 is a side view facing the outer side edge of the shoe.

Fig. 4 is a side view facing the opposite or inner side edge of the shoe.

The essential features of my design for a lady's shoe reside in the parts shown in full lines, the straps being shown fragmentarily in Fig. 2 for convenience of illustration.

I claim:

The ornamental design for a lady's shoe or similar article, substantially as shown and described.

DAVID E. LEVIN.
